R. A. WILSON

WASH DOWN PLUG

Original Filed May 6, 1921

Inventor
R. A. Wilson

Attorney
Jack Schley

UNITED STATES PATENT OFFICE.

ROBERT A. WILSON, OF DALLAS, TEXAS, ASSIGNOR TO GUIBERSON CORPORATION, OF DALLAS, TEXAS, A CORPORATION OF DELAWARE.

WASH-DOWN PLUG.

Application filed May 6, 1921, Serial No. 467,358. Renewed March 13, 1924.

To all whom it may concern:

Be it known that I, ROBERT A. WILSON, a citizen of the United States, residing at Dallas, in the county of Dallas and State of Texas, have invented certain new and useful Improvements in Wash-Down Plugs, of which the following is a specification.

This invention relates to new and useful improvements in wash down plugs.

10 It frequently occurs that before a well can be plugged to cut off the flow of bottom water, mud and sand will rise in the casing, because no means is available for pumping out the well below the plug as the latter 15 is lowered.

The object of this invention is to provide means for keeping the mud and sand in suspension by permitting a circulation of water thru the plug while the same is being 20 lowered in the casing and at the same time preventing the upward passage of water, sand and mud beyond the valve as it descends in the well and when finally seated.

A construction designed to carry out the 25 invention will be hereinafter described together with other features of the invention.

The invention will be more readily understood from a reading of the following specification and by reference to the accompanying drawings, in which an example of the 30 invention is shown and wherein:

Fig. 1 is an elevation of a plug constructed in accordance with my invention and in an expanded and unpacked condition, the 35 well casing being shown in section,

Fig. 2 is a vertical sectional detail on an enlarged scale showing the bottom nipple and the valve employed therewith,

Fig. 3 is a cross sectional detail on the 40 line 3—3 of Fig. 2,

Fig. 4 is an enlarged vertical sectional view of the upper section of the device, and

Fig. 5 is an underside view of one of the gripping slips.

45 I have illustrated my improved wash down plug in connection with a type of structure which is set forth in the patent to E. V. Crowell, No. 1,330,430, issued February 10, 1920, and a companion application Ser. No. 467,357 filed of even date here-with, but it is to be understood that the improvement consists in arranging the plug so that a circulation of liquid may be had thru the same while it is being lowered in

the well and also the prevention of a back 55 or upward flow above the plug, therefore, the exact structure of the plug is immaterial, so long as it is adaptable to the application of the invention thereto.

As a matter of convenience I have illustrated my invention in connection with the plug construction shown in the aforesaid 60 companion application. In the drawings the numeral 10 designates a tubular core or stem composed of steel or other material, 65 upon the upper end of which is arranged a sleeve 11. The sleeve has a flange 12 into the center of which the core is screw threaded. At its end the sleeve is connected to a line of pipe 13 by an ordinary collar 14. 70

Helical vanes 15 have their upper ends bolted to the flange 12 or otherwise suitably attached thereto. At their lower ends the vanes are bolted or otherwise attached to a collar 16 which is internally screw threaded 75 and receives the upper end of a nipple 17. Each vane has sufficient length to extend from the flange 12 to the collar 16 when in its extended position. The core 10 passes axially thru the vanes and telescopes into 80 the nipple 17.

At its lower end the nipple is provided with a frusto-conical counter bore 18 in which a plurality of annular wedge shaped slips 19 are arranged. I have illustrated 85 three of such slips, but it is to be understood that the number may be varied. Each slip has its inner vertical face provided with teeth and its outer face inclined at substantially the same angle as that of the 90 counter bore, whereby said slips will freely slide in said counter bore. The outer corner 19' of each slip 19 is slightly reduced so as to obviate a point which would otherwise ride on the surface of the counter bore 95 and possibly score the same. The slips are supported in the counter bore by a retaining ring 20 which is screw threaded in the lower end of the nipple. The lower end of the nipple is externally screw threaded and inserted in the upper end of the usual anchor pipe 21. The core 10 slides thru the slips 19 and the ring 20, and projects into the anchor 21. 100

The part 11 constitutes a head for driving 105 the core downwardly thru the nipple 17. It will be seen that the core is free to move downwardly thru the slips 19, but the re-

lation between the teeth of the slips and the core is such that upon an upward movement of said core, the slips will be carried upwardly in the counter bore 18, whereby the teeth will bite into the core and hold the same. It is obvious that when the flange 12, which carries the core 10, is moved toward the collar 16, the pitch of the screw formed by the vanes, will be lessened and the aggregate width from the outer edges of the vanes to the center of the core will be increased. Thus the outer edges of the vanes which are sharpened, are caused to bite into the wall of the well opening and to make lateral pressure toward the said wall, thereby digging themselves in and positively gripping the wall of the well.

The end of the core which projects below the ring 20 is externally screw threaded so as to be screwed into the upper end of a valve casing 23. A valve seat 24 is arranged in the casing and receives a valve 25 having a stem 26 passing thru a spider 27 disposed above said valve seat. A coiled spring 28 is confined on the valve stem between the spider and a head 29 on the upper end of said stem. By this arrangement the valve is drawn upwardly into the seat 24 so as to prevent the passage of a liquid into the core 10, but permitting the downward flow by unseating said valve. A similar valve 23' is mounted on the upper end of the core within the sleeve 11 and is constructed in the same manner so as to prevent an upward passage of the liquid. The valve 23' is not absolutely necessary and is used in a precautionary manner so that should the lower valve 23 become inoperative the upper check valve will operate. It is to be understood that any suitable form of check valve permitting a downward flow thru the core, but preventing an upward flow therethru, could be used and the invention is not to be limited to the details of construction which are illustrated and described.

In use the plug arranged as shown in Fig. 1, is lowered into the well. As the plug descends water may be pumped from the top of the casing down thru the core 10 and in its passage will unseat the check valves as is obvious. Should the pumping of the water stop for any reason or should its flow be overcome by a back pressure, the valves will seat and prevent a counter acting flow thru the core. The water which is pumped thru the core 10 creates a circulation down thru the casing so that the mud and sand is held in suspension and prevented from packing or settling. This is very important as it keeps the hole free and enables the plug to be seated at the desired place. When the plug is in proper position the anchor pipe 21 which is of suitable length, engages the bottom of the well. The plug is lowered below the casing and the

helical vanes do not engage the side walls of the casing, but engage in the wall of the well hole. Tools are used to force the sleeve 11 downwardly toward the ring 20. The core 10 passes thru the slips 19 which act to prevent a reverse movement of said core and to hold the vanes in a compressed position. The vanes grip the well wall and after the device is in proper position, cement or other packing material may be introduced as much being added as may be desired. In order to provide a means for holding a sealing medium in the helical vanes, a number of openings 22 are provided in the edges of the vanes and serve as anchorage for the sealing medium, and thru which wires not shown, may be run if desired to better hold the sealing medium in place, this being a common expedient, illustration is not deemed necessary. As the invention relates to the tubular core and the check valves, it is not believed necessary to go into the details of the manner of seating and packing the plug.

Various changes in the size and construction of the parts as well as modifications, may be made without departing from the spirit of the invention.

What I claim, is:

1. In a wash down plug apparatus, the combination with a pipe line, of a sleeve secured to its lower end, said sleeve having a head at its lower end and provided within said head with an opening, a tubular core having a smaller diameter than the pipe line and having its upper end held within the opening of said head with the head extending laterally beyond the tubular core, an anchor pipe to engage the bottom of the same, a tubular nipple secured to the anchor pipe and slidably receiving the tubular core, said tubular nipple extending radially beyond the core and the core projecting downwardly beyond the tubular nipple, helical vanes surrounding the tubular core and connected with the head of the sleeve and the nipple, and a check valve structure embodying a valve casing secured to the lower end of the tubular core and beneath the nipple and arranged within the anchor pipe, said check valve structure providing means whereby the circulation of water may be had downwardly through the anchor pipe and upwardly exteriorly of the same.

2. In a wash down plug apparatus, the combination with a pipe line, of a coupling element connected therewith, a tubular core connected with the coupling element and having a smaller diameter than the pipe line, a tubular coupling slidably receiving the lower portion of the tubular core and extending radially beyond the same, means for effecting a locking engagement between the tubular nipple and core, flexible means arranged between the sleeve and tubular nip-

ple, and surrounding the tubular core, an anchor pipe secured to the lower end of the tubular nipple with the tubular core projecting downwardly below the tubular nipple to enter the anchor pipe, and a check valve structure embodying a valve casing mounted within the anchor pipe beneath the

tubular nipple and secured to the lower end of the tubular core, said check valve structure providing means whereby water may be circulated downwardly within the anchor pipe and upwardly exteriorly thereof.

In testimony whereof I affix my signature.
ROBERT A. WILSON.
